UNITED STATES PATENT OFFICE

166,575

SEWING MACHINE

Hector Rabezzana, Fenton, Mich.

Application April 5, 1951, Serial No. 14,714

Term of patent 14 years

(Cl. D70—1)

To all whom it may concern:

Be it known that I, Hector Rabezzana, a citizen of the United States of America, residing in the village of Fenton, in the county of Genesee, State of Michigan, have invented a new, original, and ornamental Design for a Sewing Machine, of which the following is a specification, reference being had to the accompanying drawings, forming a part thereof, wherein:

Figure 1 is a perspective view of a sewing machine showing my new design;

Figure 2 is an end elevation showing the left-hand end of the sewing machine as viewed in Figure 1;

Figure 3 is an end elevation showing the right-hand end of the sewing machine as viewed in Figure 1;

Figure 4 is a front elevation of the sewing machine shown in Figure 1; and

Figure 5 is a rear elevation of the sewing machine shown in Figure 1.

The essential features of my design reside in that portion of the design illustrated in solid lines.

I claim:

The ornamental design for a sewing machine, as shown and described.

HECTOR RABEZZANA.
